UNITED STATES PATENT OFFICE

162,937

ASH TRAY

Robert C. Dixon, Idaho Springs, Colo.

Application April 13, 1950, Serial No. 9,180

Term of patent 7 years

(Cl. D85—2)

To all whom it may concern:

Be it known that I, Robert C. Dixon, a citizen of the United States, residing at the city of Idaho Springs, county of Clear Creek, and State of Colorado, have invented a new, original, and ornamental Design for Ash Tray, of which the following is a specification, reference being had to the accompanying drawing, forming a part hereof.

Figure 1 is a perspective view of an ash tray showing my new design; and

Figure 2 is a top plan view thereof.

I claim:

The ornamental design for an ash tray, as shown.

ROBERT C. DIXON.
